ELECTRICALLY CONTROLLED LOCK

James M. Wilhelm, Marietta, Ohio

Application September 3, 1935, Serial No. 38,997

1 Claim. (Cl. 292—144)

This invention relates to electrically controlled locks and more particularly to locks of this character applied to automobile gasoline tanks, and has for an object to provide novel means controlled by a normally open circuit for locking the cap to the filling tube, the circuit closing switch being located within the vehicle body so that opening of the cap by unauthorized persons will be positively prevented.

10 A further object is to provide a signal device preferably a lamp bulb, a normally open circuit, and a circuit closer in the circuit controlled by opening and closing of the cap to energize the lamp during the period the cap is open and extinguish the lamp when the cap is closed.

15 A further object is to provide a device of this character which will be formed of a few, strong, simple, and durable parts, which will be easy to manufacture, and which will not easily get out of order.

20 With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of 30 this specification,

Figure 1 is a longitudinal sectional view through an electrically controlled gasoline tank lock constructed in accordance with the invention.

Figure 2 is a cross sectional view taken on the 35 line 2—2 of Figure 1.

Figure 3 is a front elevation of the manually controlled circuit closer in applied position on the instrument board of the motor vehicle.

Referring now to the drawing in which like 40 characters of reference designate similar parts in the various views, 10 designates the filling tube of a motor vehicle gasoline tank, and 11 designates the cap for the filling tube, the cap being hinged as shown at 12 to a base ring 13 which is threaded 45 on to the upper end of the filling tube. The cap is preferably provided with an annulus 14 which is integrally connected with the arched top of the cap by webs 15 and the bore of the annulus registers with the bore of the base ring 13. The 50 annulus and the base ring are spaced sufficiently apart to receive packing washers 16 and 17 carried respectively by the annulus and the base ring.

A latch 18 is pivotally mounted at the upper end on a pin 19 carried by a lug 20 which is integral 55 with the underneath face of the arched top of the

cap 11. The latch depends from the cap and enters the filling tube and is held rocked on the pivot toward one side of the filling tube by means of a helical spring 21 which is interposed between a projection 22 on the latch and the underneath 5 face of the lug 20. A stop tooth 23 on the latch engages an abutment 24 on the lug and limits rocking movement of the latch toward the side of the tube.

A solenoid 25 is disposed on the exterior of the 10 filling tube below the base ring 13 and is concealed in a housing 26 which is secured to the tube by screws 27 or other suitable connectors. The solenoid is provided with a core 28 which is spring pressed outwardly by means of a helical spring 29 15 disposed in the solenoid in rear of the core. The core is provided at the outer end with a tongue 30 which projects through an opening formed in the filling tube and engages in a notch 31 formed in the latch 18 to normally hold the cap locked in 20 closed position on the filling tube.

For energizing the solenoid to withdraw the core from the latch and permit the cap to be opened, a circuit closer is provided within the body of the vehicle, and preferably is located on 25 the instrument board 32. The circuit closer, in the present embodiment of the invention, comprises a cylindrical housing 33 which is passed through an opening 34 in the instrument board and is secured to the instrument board by a nut 35 threaded on to the housing and engaged against the rear face of the instrument board, and a flanged nut 36 threaded into the bore of the housing and engaged against the front face of the instrument board. A push button 37, preferably 35 formed of glass is slidably fitted in the flange of the nut 36 and is held at its outer limit of movement against a stop shoulder 38 on the nut, by means of a leaf spring 39 which is secured to, and insulated from, the inner wall of the housing as 40 shown at 40.

The housing 33 is closed at the end opposite the push button by means of a disc 41 of insulating material and binding posts 42 and 43 are mounted on the disc. A conductor wire 44 is connected at 45 one end to the binding post 42 and bears at the opposite end against the leaf spring 39. A conductor wire 45 is connected at one end to the binding post 43 and bears at its opposite end against a switch contact 46 which is insulated from the 50 housing and is in the path of movement of the spring 39 when deformed by movement of the push button 37 inwardly, to close the circuit for energizing the solenoid 25.

The binding post 42 is connected by a con- 55

ductor wire 47 to a binding post 48 which is carried by and insulated from the solenoid housing 26, one end of the solenoid coil being connected to the binding post by means of a wire 49 and the 5 opposite end of the solenoid coil being grounded to the housing as shown at 50. From the battery 51 a conductor wire 52 is led to a binding post 53 on the insulating disc closure 41 of the push button housing. The binding post 53 is in contact 10 with the center terminal of a lamp bulb 54, the other threaded terminal 55 of the bulb being screwed into a socket 56 which is connected by a clip 57 to the conductor wire 45.

The energizing circuit of the solenoid 25 is normally open. When the push button 37 is depressed a closed circuit may be traced from the battery 51 through the wire 52, signal lamp 54, clip 57, conductor wire 45, fixed contact 46, spring switch contact 39, conductor wire 44, wire 47, and solenoid coil to the ground, to energize the solenoid and withdraw the core 28 from the latch 18. During energizing of this circuit the signal lamp 54 will glow and illuminate the transparent push button 37 upon which is preferably marked the 25 word "open" as shown at 58 in Figure 3.

Upon release of the push button 37 the energizing circuit for the solenoid is broken by disengagement of the spring contact 39 from the fixed contact 46 but it will be here pointed out that the signal lamp 54 is maintained in a glowing condition by a circuit closer operated by opening movement of the cap and controlling an associated circuit as will now be described. A housing 59 is provided with a marginal flange 60 through which screws 61 are passed into the filling tube 10. The housing is arranged below the hinged end of the cap. A binding post 62 is secured to the housing and insulated therefrom and is connected by a conductor wire 63 to the binding post 43 of the signal lamp housing 33. A stationary switch contact 64 is arranged on the housing 59 above the binding post 62 and is grounded to the housing. A U-shaped movable switch contact 65 is slidably mounted on the binding post 62, there being a slot 66 in one leg of the switch contact loosely receiving a reduced neck 67 of the binding post. The same leg of the movable contact is bifurcated at the end as shown at 68 to embrace a reduced neck 69 on the fixed contact 64 to close the circuit through the wire 63 when the movable contact is slid upwardly into engagement with the fixed contact.

A rod 70 is slidably fitted in superposed openings in the housing 59 and base ring 13 and is pivotally connected at the lower end to the free leg 55.

of the movable switch contact 65 as shown at 71. The upper end of the rod is provided with a head 72 which is pressed downward by the cap 11 to seat on the base ring 13 in which position the rod holds the movable switch contact 65 open. A 5 helical spring 73 is mounted on the rod and is confined under tension between a stop collar 74 on the rod and the top of the housing 59. The spring tends to normally hold the rod raised and the movable switch contact closed. 10

When the solenoid 25 is energized to withdraw the core 28 from the latch 18 the cap is unlocked and simultaneously therewith the spring 73 urges the rod 70 upward to swing open the cap and engage the movable switch contact 65 with the fixed 15 switch contact 64 to maintain the signal lamp 54 in glowing condition until the cap is closed. When the cap is manually closed after the gasoline supply has been replenished the cap forces the rod 70 downward to disengage the movable 20 switch contact 65 from the fixed switch contact 64 and open the energizing circuit of the signal lamp.

From the above description it is thought that the construction and operation of my invention 25 will be fully understood without further explanation.

What is claimed is:

A latching device for use with a gasoline filling tube and a hinged cap for the tube having a 30 spring connected to the cap and to the tube for opening the cap, comprising a latch adapted to be pivotally mounted on the bottom face of the cap and extend into the tube, a spring connected to the latch adjacent to the pivot for normally holding the latch pressed toward the tube in operative position, a solenoid, a spring pressed core for the solenoid having a tongue adapted to project laterally into the interior of the tube below the upper end thereof and having a terminal cam surface, a head on said latch having a notch receiving the extreme end of said core to hold the cap closed against the tension of its controlling spring, there being a cam surface on the head below the notch engageable with the cam surface of the core to permit the latch riding over the core when the cap is closed until the extreme end of the core registers with said notch, the controlling spring of the latch forcing the latch to operative position with the tongue fitted in the extreme end of the notch and lock the cap closed, and means for energizing the solenoid to withdraw the core from the notch and permit the controlling spring of the cap to swing the cap open.

JAMES M. WILHELM. 55
